UNITED STATES PATENT OFFICE.

THOMAS HENNING, CHARLES E. HENNING, AND WILLIAM J. HENNING, OF PASADENA,
CALIFORNIA.

GAS-METER.

No. 876,875.

Specification of Letters Patent.

Patented Jan. 14, 1908.

Application filed March 13, 1907. Serial No. 362,236.

To all whom it may concern:

Be it known that we, THOMAS HENNING, a subject of the King of the United Kingdom of Great Britain and Ireland, and CHARLES E. HENNING and WILLIAM J. HENNING, citizens of the United States, residing at Pasadena, in the county of Los Angeles and State of California, have invented new and useful Improvements in Gas-Meters, of which the following is a specification.

This invention relates to gas meters of the type wherein a plurality of diaphragms actuated by the gas pressure operate sequentially on crank means to produce motion of the dial and valve means are provided controlled by such motion to give the successive operation of the diaphragms.

An object of this invention is to improve the general construction of such meters with a view to facilitating the construction, assembly and adjustment thereof.

A further object of the invention is to provide improved means for securing in place the movable diaphragm of the pressure chambers.

Another object of the invention is to provide improved means for adjusting the operating connection to the crank shaft.

Another object of the invention is to provide means for accurately adjusting the crank or tangent devices for connecting motion to the valve means.

Another object of the invention is to provide improved means for securing the dial mechanism in place in such manner that it can readily be removed and replaced.

In the accompanying drawings:—Figure 1 is a horizontal section of the meter on the line x^1-x^1 in Fig. 3. Fig. 2 is a horizontal section on line x^2-x^2 in Fig. 3. Fig. 3 is a vertical section on line x^3-x^3 in Fig. 1. Fig. 4 is a vertical section on line x^4-x^4 in Fig. 1. Fig. 5 is a front elevation of the dial receiving portion of the case, with the dial in place. Fig. 6 is a section of an adjustable crank or tangent means for operating the valve for the pressure operated means. Fig. 7 is an axial section of the valve.

The meter comprises a case 1 formed preferably as a cylindrical shell of sheet metal having its ends closed by removable caps or plates 2. The space within the shell is divided into three pressure chambers by two diaphragm members 3, 4, which are con-

nected to the walls of the case by flexible fabric means indicated at 5 fastened to said diaphragms and detachably secured to the wall of the case by expansion rings 6 pressing the peripheral portions of said flexible means into grooves 7 in the case. Said expansion rings are split so that, when they are brought into position, they can be expanded to bind the flexible means firmly in place and can then be secured by solder indicated at 8.

A bail or swinging member 11 is pivoted at each side of the case and engages within slotted lugs 13 on the diaphragm to guide the diaphragm in its movement, so that it will have a parallel in and out motion.

A shaft 9 is journaled in bearing 10 in the case and is connected to the respective diaphragms 3, 4 by connecting means herein-after described. An arm 12 is pivoted at each side of the case and extends inwardly to the mid width of the case and then upwardly to form a pivot portion which is pivoted in brackets 14 on the outer side of the corresponding diaphragm. A link 15 is pivoted on such pivot portion of one of said arms and is pivotally connected at its other end to a crank 16 on the shaft 9 aforesaid. A link 17 is similarly pivoted on the pivot portion of the other arm 12 and is pivoted at its other end to a block 18 slidably mounted in a guide 19 formed in an arm 20 rigidly connected to the said crank 16. A screw 21 working in said arm 20 serves to adjust said block in either direction in said guide. The end of said screw is provided with operating means such as a flattened portion 22, and holes 23 are provided in opposite sides of the case, said holes being normally closed by plugs 24, and being so located that when the said plugs are removed the said adjusting means is directly in the line of vision between the two holes and can be both inspected and adjusted from the outside of the case without opening up the case or removing the diaphragms, a tool indicated in dotted lines at 25 being inserted to turn the screw 21.

A sheet metal tubular case portion 27 extends upwardly from the top of the case 1 and is formed with a flat floor 28 and with a central valve seat portion 29 on the upper surface of which travels the valve 30, said valve being formed as a disk. An inlet pipe 26 leads downwardly alongside the case extension 27, and communicates with a riser

38, which extends up above the floor 28 and opens into the chamber above the valve, so that the gas passing in through this inlet impinges downwardly on the valve. Said valve seat portion 29 is formed with a central portion 31 and with three outer openings 32, 33, 34 arranged around the central opening. The central opening communicates by a duct 35 to an outlet pipe or tube 36 and two of the outer openings communicate by duct 37 with the pressure chambers at opposite ends of the case. The remaining outer opening 34 communicates directly with the middle pressure chamber.

15. The crank shaft 9 is provided at its upper end with a crank or tangent which is adjustable to vary the rotating or angular position of the crank on the shaft and thereby adjust the operation of the meter. To effect this 20 adjustment said crank is made in two portions, the lower portion 40 being rigidly secured on the shaft 9 by a set screw 41, and the upper portion 42 screwing on the screw-threaded upper end of said shaft and being 25 clamped in any desired rotative position, within certain limits, by means of a set screw 43 screwing therethrough and engaging the upper surface of said crank portion 40. The crank member 42 has a pin 44 engaging in a 30 central hole or socket 45 in the bottom of valve disk 30. Said valve disk is preferably of glass and is protected at its outer portion by a plate 47 of metal crimped or cemented thereon. The socket 45 is in a hub protected 35 by a collar 46 of metal.

At the front of the upper portion or extension 27 of the case is provided a rectangular seat or box 39 for receiving the dial, having a screw socket to receive a screw plug 48 with an inwardly extending bracket 49 carrying a shaft 50 rotatably mounted therein, and having a crank 51 with an opening 52 to fit over a nib 53 on the valve disk 30. A worm 54 on said crank 51 on said shaft 50 is 45 secured thereto by a detachable pin 55 and engages a worm 56 on a shaft 57 which extends through the plug 48 into the dial receiving box, said shaft 57 being provided at its outer end with a kerf or notch 58, this 50 portion of the shaft 57 being located within a seat portion 59 in the dial receiving box. The dial 60 consists of any usual counter wheel means, the lowest wheel of the series having an extension 61 projecting rearwardly from the case of the dial and formed 55 so as to engage with the notch in the end of the shaft 57 aforesaid when the dial is pushed rearwardly in the case, thereby operatively connecting said shaft with the dial mechanism. To guide the dial to proper position when thus pushed into the dial receiving box, said box is provided with guides 63 engaging 60 ways 64 on the dial. The top of the upper case member 27 is closed by a cap plate 65.

65. The outer case is preferably formed of

sheet metal throughout. To prevent corrosion and penetration of the bottom of the case when it is set on the ground, a flat bottomed sheet metal extension 66 is formed on the bottom of the case.

The dial receiving box is closed at the front by a cover box 67 fitting and sliding over box portion 39 and having a hinged door 68. Said cover box 67 is fastened by a screw 69. A glass plate 70 is placed in box 39 being supported by corner pins 71 and held in by the cover box 67.

The gas enters through passage 26 and passes upward through the passage 38 into the valve chamber, being thus delivered to 80 the upper part of the chamber in an upward direction so that it comes down on top of the valve and there is no tendency to lift the valve by the gas flow. From this valve it passes down through one of the ports, say 34, to say the middle pressure chamber in the meter, the crank connections to the shaft 9 being such that in this position in Fig. 1 there is a differential action on the shaft, tending to rotate the shaft, and in such rotation the valve is shifted successively to the different ports, opening communication to the successive pressure chambers so as to always produce a rotative force on the shaft. The resulting rotation is communicated to 95 the dial through the members 54, 57, etc. It will be noted that the fastening screw 69 for the dial cover is on the inside of the case, so that it is protected or sealed against tampering by the seal of the closure plate 65 at 100 the top of the case. Said closure plate being generally soldered in place it is therefore not possible for anyone to tamper with the dial.

What I claim is:—

1. In a gas meter, the combination with a cylindrical case, of the diaphragm therein provided with a flexible portion extending to the wall of the case, said wall having an annular groove to receive said flexible portion, in combination with a clamping ring 110 extending within said flexible portion and pressing the same outwardly into the groove.

2. In a gas meter, the combination with a case, of movable diaphragms therein provided with flexible portions extending to the walls of the case, and a swinging member pivoted on the walls of the case at opposite sides and extending across the case and having pivotal connection to the diaphragms, to 115 guide the same in its movement.

3. In a gas meter, the combination with a case and the removable diaphragms, of a shaft rotatably mounted in the case and having a crank, a link connection from one 125 diaphragm to said crank, an arm rigidly carried by said crank, a member adjustable on said arm, and a link connection from said member to the other diaphragm, the case having diametrically opposite openings in 130

- line with one position of said adjustable means, and removable means for closing said openings.
4. In a gas meter, the combination with the operating crank shaft and the rotary valve member, of an adjustable crank means connecting said shaft and member and comprising two angularly adjustable members, one connected to the crank shaft and the other having pivotal connection with the valve member.
5. In a gas meter, the combination with the gas pressure operated shaft, provided with an adjustable crank, a rotary valve operated by the crank, another shaft having crank connection to the valve member to be operated thereby, a worm and detachable means for securing it to its shaft, and a dial operating worm wheel engaging said worm.
6. In a gas meter, a rotary valve member formed of a glass disk having a flat lower face, the said disk being protected by sheet metal crimped over the outer portion of the top thereof.
7. In a gas meter, a rotary valve member

formed of a glass disk having a flat lower face, the said disk being protected by sheet metal crimped over the outer portion of the top thereof, and having a hub in the central portion of its bottom formed with a crank pin 30 receiving socket and protected by a metal collar around said hub.

8. In gas meter, a case formed with a dial receiving box portion, a cover box sliding and fitting over said box portion and a glass 35 plate in the front of the box portion and held in by the cover box, fastening means inside of the case engaging with the cover box to hold it in place, the case being formed with a sealed closure, normally preventing access to 40 the said fastening means.

In testimony whereof, we have hereunto set our hand at Los Angeles, California, this 2nd day of March, 1907.

THOMAS HENNING.
CHARLES E. HENNING.
